CLAIM

The ornamental design for a handset telephone unit, as shown.

DESCRIPTION

FIG. 1 is a perspective view from above of the front, top and one side of a handset telephone unit showing our new design;

FIG. 2 is a side elevational view thereof;

FIG. 3 is a front elevational view thereof;

FIG. 4 is a rear elevational view thereof;

FIG. 5 is a side elevational view thereof of the side opposite that shown in FIG. 2;

FIG. 6 is a top plan view thereof; and

FIG. 7 is a bottom view thereof.

FIG. 3

FIG. 4

FIG. 5

FIG. 6

FIG. 7
